IMPROVEMENT IN CAR BRAKES.

DAVID MYERS, OF CHICAGO, ILLINOIS.

Letters Patent No. 60,228, dated December 4, 1866.

SPECIFICATION.

TO ALL WHOM IT MAY CONCERN:

Be it known that I, DAVID MYERS, of Chicago, in the county of Cook, and State of Illinois, have invented a new and useful Improvement in Car Brakes; and I do hereby declare and make known that the following is a full, clear, and exact description of the same, reference being had to the accompanying drawings, and the letters and figures marked thereon, which form part of this specification.

My invention consists in a novel arrangement of mechanical devices to be attached beneath each of the cars composing a train, and connected by a suitable cord to the ordinary bell-cord running through the train to the engine, wherein a spring is so applied that it may be wound up to any desired degree of tension, and upon being released by the pulling upon the bell-cord by the engineer, its contractile power will operate to apply the brakes; and whereby, by giving a second pull upon the bell-cord, the engineer may, in like manner, release the subsidiary tension which holds the brakes upon the wheels, and thus open the brakes when desired.

To enable those skilled in the art to understand how to construct and use my invention, I will proceed to describe the same with particularity, making reference in so doing to the aforesaid drawings, in which—

Figure 1 represents a bottom view of a car with my invention attached.

Figure 2, a side elevation of the same.

Figure 3 is a top view of my said invention.

Figure 4 is a side view of the same; and

Figure 5 represents a top and side view of the head of the pawl, P.

Similar letters of reference in the several figures indicate the same parts of my invention.

X represents a suitable case enclosing the operating parts of my invention, and attached transversely beneath the car, as shown. m represents a vertical shaft having bearings in the top and bottom of the case, X, as shown, having attached thereto within the case a horizontal cam or wheel, C, and having upon its lower end, exterior to the casing, a box, M, with open sides, in which are supported two small shives, h, as shown, between which passes a cord or chain, o, which is connected with the brake-rod and levers, as clearly shown in fig. 1. F represents the spring or springs whose contractile force operating upon the cam, C, applies the brakes, to one end of which a cord or chain, D, is attached, which passes around a shive, E, and goes to be secured to the cam-wheel, C, at C', passing around a series of pins forming a cam for the chain on the cam-wheel, C, as clearly shown in fig. 3, while another cord or chain, d, passes from the other end of the spring around a vertical shaft, T, upon which is fixed a ratchet-wheel, H, as shown. I represents a rod extending from one end of the car to the said ratchet-wheel, being provided with a hook on the end, as shown at the wheel H, and a vertical shaft or crank-lever at the other end, marked L, which is attached to the end of the car or the platform thereof. The spring, J, is so arranged as to hold the hook or rod, I, against the ratchet-wheel, H, and the spring, K, draws the rod and hook back in a longitudinal direction from the teeth of the ratchet-wheel, H, when moved towards the end of the car, as hereinafter specified. P represents a pawl which holds into the teeth of the ratchet-wheel, H, and prevents it from revolving in the wrong direction when the spring, F, is wound up. The pawl is held down upon the wheel, H, by means of a spring, Q, at its opposite end. B represents a lever or stop, an end of which enters a notch, c, upon the face of the wheel C, and prevents the tension of the spring from revolving the cam-wheel C and shaft m, until said lever, B, is withdrawn, as hereinafter specified. The opposite end of said lever, B, is provided with a slot, and connected, by means of a pin passing through said slot, with an elbow-lever, A, pivoted at b, to one arm of which a cord, a, is attached, which goes up and is fastened to the bell-cord in any suitable manner, so that pulling upon said bell-cord, or upon the cord a, will withdraw the lever B from the notch c and apply the brakes. To the upper part of the elbow-lever, A, is pivoted an arm, R, which lies under the pawl, P, and is provided with a shoulder at l, as shown. The outer end of the arm, R, is supported upon the end of a spring, S, which passes loosely between the pins s s, as shown in fig. 4, the opposite end of said spring being fastened to the lever B, said lever having a longitudinal motion, but prevented from any lateral movement by the stops D', arranged as shown. The ratchet-wheel, H, has a smooth face under the teeth, of a less diameter, marked N, as seen in fig. 4, and the pawl-head is jointed, as shown in fig. 5, so that when thrown or pushed from the wheel H by the arm R, as hereinafter described, the point t is folded back inwards towards the wheel, bringing a projecting bearing, u, in contact with the smooth periphery, N, and allowing the said shaft,

T, of wheel H, upon which the cord d is wound, to revolve until all the tension is taken off from spring F, so that the point of the pawl will not press upon the teeth of the ratchet-wheel H.

Having described the construction of my invention, I will now describe its operation. The spring F is drawn to the required degree of tension by giving an oscillating or reciprocating motion to the crank L, whereby the hook upon the end of the rod I is caused to turn the ratchet-wheel H and its shaft, the pawl P holding the wheel in place while the hook is moved back to repeat the operation, the chain d being thus wound upon the shaft T, effecting the purpose desired. When the apparatus is thus arranged, the arm R is low enough to slide under the pawl P without bringing the offset or shoulder l against said pawl. The apparatus being in readiness, the engineer, desiring to stop the train, pulls upon the bell-cord, to which the cord a is attached, and thus pulls upon the elbow-lever A, which has the effect to withdraw the bar B from the recess, e, in the cam C, and at the same time to thrust the arm R forward beneath the pawl P, sliding its outer end upwards on its elastic support S. By the withdrawal of the bar B from the recess, e, in the cam C, the spring F, acting upon the chain D, revolves said cam and its shaft, m, and the block M, thereby taking up and shortening the cord or chain e, and applying the brakes as desired, while the shives h permit the chain O to slide so as to equalize the pressure of the brakes upon both trucks. From the configuration of the said cam, C, and its revolution, as aforesaid, it forces the bar B back towards the arm A, the slot in the end thereof allowing said movement, the effect of which is to thrust the spring S back far enough to bring the shoulder l above the lower side of the pawl P, so that the engineer by giving a second pull upon the bell-cord can, by the movement of the arm R and shoulder l against the pawl P, force said pawl away from the ratchet-wheel H, the tooth t turning back, as aforesaid, and thus turn off the tension from the spring F, releasing the brakes as desired, when the spring G brings the cam C back to its place, and the spring F may again be wound up to be ready for another operation.

Having described the construction and operation of my invention, I will now specify what I claim, and desire to secure by Letters Patent:

1. I claim the combination of the cam-wheel C, shaft m, chain D, and spring or springs F, arranged and operating substantially as and for the purpose specified and shown.
2. I claim, in combination with cam-wheel C and shaft m, the box M and shives h, arranged substantially in the manner and for the purposes set forth.
3. I claim, in combination with cam-wheel C, provided with a recess, e, the bar B and elbow-lever A, arranged and operating as described, and for the purposes specified.
4. I claim providing the ratchet-wheel H with the smooth periphery or flange N, when arranged in combination with the projection u upon the point t of the pawl P, and operating substantially as described.
5. I claim the arrangement of the arm R, provided with a shoulder, as described, with the elbow-lever A and pawl P, operating substantially in the manner and for the purposes specified.
6. I claim, in combination with said bar R, the arrangement of the movable elastic support or spring, S, operating substantially as and for the purposes herein shown and described.

D. MYERS.
